UNITED STATES PATENT OFFICE

JOHANNES H. WENDT, OF EVANSTON, ILLINOIS

DESIGN FOR AN AEROPLANE

Application filed April 10, 1930. Serial No. 35,447. Term of patent 14 years.

To all whom it may concern:

Be it known that I, JOHANNES H. WENDT, formerly a citizen of the German Empire, and now having declared my intention of becoming a citizen of the United States by filing my first papers, residing at Evanston, in the county of Cook and State of Illinois, have invented a new, original, and ornamental Design for an Aeroplane, of which the following is a specification, reference being had to the accompanying drawing, forming a part thereof.

Figure 1 is a top plan view of the device illustrating my new design;

Fig. 2 is a front elevational view of Figure 1, depicting a low-wing boat type seaplane, wherein the elongated wings extend substantially midway from the opposite sides of the hull of the boat; and

Fig. 3 is a side elevational view thereof.

I claim:

The ornamental design for an aeroplane substantially as shown and described.

JOHANNES H. WENDT.
